UNITED STATES PATENT OFFICE

167,662

SEPARABLE COUPLING FOR HYDRAULIC LINES

Raymond M. Ulrich, Roanoke, Ill., assignor to
 Ulrich Foundation, Inc., a corporation of Delaware

Application March 29, 1951, Serial No. 14,656

Term of patent 7 years

(Cl. D91—3)

To all whom it may concern:

Be it known that I, Raymond M. Ulrich, a citizen of the United States, residing at Roanoke, in the county of Woodford and State of Illinois, have invented a new, original, and ornamental Design for Separable Coupling for Hydraulic Lines, of which the following is a specification, reference being had to the accompanying drawing, forming a part thereof.

Figure 1 is a plan view of a separable coupling for hydraulic lines, showing my new design;

Figure 2 is a front view of the device shown in Figure 1; and

Figure 3 is a side view of the same device shown in Figures 1 and 2.

I claim:

The ornamental design for a separable coupling for hydraulic lines, as shown.

RAYMOND M. ULRICH.
